UNIT FOR A MODULAR INSTRUMENT PANEL FOR A BOAT OR THE LIKE

Richard J. McFadyen, Upper Montclair, N.J., assignor,
by mesne assignments, to Aqua Meter Instrument Corporation, Roseland, N.J., a corporation of New Jersey

Filed Sept. 27, 1961, Ser. No. 66,883

Term of patent 14 years

(Cl. D52—6)

FIG. 4

FIG. 1

FIG. 2

FIG. 5

FIG. 1 is a top plan view of a unit for a modular instrument panel for a boat or the like showing my new design;

FIG. 2 is an elevational view taken from the left side thereof;

FIG. 3 is a front elevational view thereof;

FIG. 4 is an elevational view taken from the right side thereof; and

FIG. 5 is a bottom plan view thereof.

I claim:

The ornamental design for a unit for a modular instrument panel for a boat or the like, as shown.
